(57) CLAIM

The ornamental design for a cosmetic sponge, as shown and described.

DESCRIPTION

FIG. 1 is a top perspective view of an embodiment of a cosmetic sponge.

FIG. 2 is a bottom perspective view of the cosmetic sponge shown in FIG. 1.

FIG. 3 is a front view of the cosmetic sponge shown in FIG. 1.

FIG. 4 is a side view of the cosmetic sponge shown in FIG. 1.

FIG. 5 is a rear view of the cosmetic sponge shown in FIG. 1.

FIG. 6 is a top view of the cosmetic sponge shown in FIG. 1; and,

FIG. 7 is a bottom view of the cosmetic sponge shown in FIG. 1.

The dashed lines in FIGS. 1 through 7 represent features of the cosmetic sponge which form no part of the claimed design in the respective embodiments.

1 Claim, 2 Drawing Sheets
